UNITED STATES PATENT OFFICE.

HERBERT A. WALLACE, OF NEW YORK, N. Y., ASSIGNOR TO THE UNION SWITCH & SIGNAL COMPANY, OF SWISSVALE, PENNSYLVANIA, A CORPORATION OF PENNSYLVANIA.

RAILWAY SIGNALING.

1,163,720.

Specification of Letters Patent. Patented Dec. 14, 1915.

Application filed June 23, 1914. Serial No. 846,729.

To all whom it may concern:

Be it known that I, HERBERT A. WALLACE, a citizen of the United States, residing at New York, in the county of New York and State of New York, have invented certain new and useful Improvements in Railway Signaling, of which the following is a specification.

My invention relates to railway signaling, 10 and particularly to signaling for two or more parallel tracks on bridges or other localities where it is desirable, for purposes of safety, to limit the number of trains which may simultaneously occupy a given territory, such, for example, as the territory in 15 the middle of a bridge span or a railway station.

I will describe several forms of signaling embodying my invention, and will then 20 point out the novel features thereof in claims.

In the accompanying drawings, Figure 1 is a diagrammatic view showing two parallel tracks over which traffic moves in opposite directions, and one form of signaling system embodying my invention for preventing more than one train from occupying a restricted territory. Fig. 2 is a view 25 showing two parallel tracks over which traffic moves in the same direction, and one form of signaling system embodying my invention for preventing more than one train on either track from occupying a restricted territory.

Similar reference characters refer to similar parts in each of the views.

Referring first to Fig. 1, W and E designate two parallel railway tracks over which traffic moves in opposite directions as indicated by the arrows. A—B is a restricted territory, that is, a territory in which only a limited number of trains are allowed at one time. For example, this territory may be the middle of a bridge span between two piers 10, 10. In the form of my invention shown herein, only one train is permitted in the restricted territory at a time, that is, if a train occupies track W between A and B, then a train on track E must not enter 45 this territory. To thus limit the number of trains in the restricted territory, I provide signals and signal-controlling means such as I will now describe.

Traffic into the restricted territory A—B on track W is governed by a signal S^W located adjacent the entrance end of the territory, and traffic into the same territory on track E is similarly governed by a signal S^E also located adjacent the entrance end of the territory. The rails of track W within 50 the restricted territory are electrically separated from the adjacent portions by insulations 2 at points A and B, and form part of a track circuit which also includes a source of current b , here shown as being a battery, 55 and a track relay T' . Track E is provided with a similar track circuit which includes the rails of the restricted territory, a battery b and a track relay T^E . Each track is also provided with a preliminary section extending to the rear from the restricted territory, which sections are designated B—D and A—C respectively, and each of these preliminary sections is provided with a track circuit comprising the track rails, a 60 battery b , and a track relay, which latter relays are designated T and T^E respectively. The limitations of these preliminary track circuits are determined by insulations 2 at the points C and D.

For each signal S^W and S^E I provide a signal relay, which relays are designated R^W and R^E respectively, and each of which relays is controlled by the track relay of the preliminary track circuit for the other track. 65 For example, the circuit for signal relay R^W is from battery 3 through wires 4 and 5, contact 6 of relay T^E , wires 7 and 29, relay R^W , common wire O to battery 3. Hence, relay R^W is closed only when preliminary 70 section A—C is unoccupied. Signal relay R^E is provided with a similar circuit which is controlled by contact 6 of track relay T of preliminary section B—D.

Each of the signals S^W and S^E is controlled by the corresponding signal relay R^W or R^E , and also by both track relays T' and T^E of the track circuits in the restricted territory. For example, the circuit for the control of signal S^W is from battery 3 through wires 4 and 14, contact 15 of track relay T^E , wire 16, contact 17 of track relay T' , wire 18, contact 19 of relay R^W , wire 20, signal S^W , wire 21 and common wire O to battery 3. The circuit for signal S^E is similar, being controlled by relays R^E , T' and 105

T³. The track relays for the preliminary sections may also, if desired, be employed to control other signals for their own tracks.

For a reason which will appear hereinafter, the circuit for each signal relay R^W and R^E is provided with means for removing the corresponding relay from the control of the track relay for the opposite preliminary section, and this means is controlled by the 10 other signal relay. As here shown, the means for removing relay R^W from the control of track relay T² is a shunt around contact 6 of the latter relay, which shunt comprises wire 8, back contact 9 of signal relay 15 R^E, and wire 10. Similarly, the circuit for signal relay R^E is provided with a shunt around contact 6 of track relay T, which shunt comprises wire 11, back contact 12 of relay R^W, and wire 13.

20 The operation of the apparatus thus far described, is as follows: If an eastbound train on track E enters preliminary section C—A, the consequent opening of track relay T² opens the circuit for signal relay R^W so that signal S^W changes to "stop" indication and thus prohibits the entrance of a westbound train into the restricted territory A—B. As the eastbound train enters the restricted territory A—B, the consequent 25 opening of track relay T³ opens the circuits for both signals, thus holding signal S^W at stop and placing signal S^E at stop. This condition of the signals is maintained until the train leaves the restricted territory, 30 when both signals return to "proceed" position unless one or the other of the preliminary sections is occupied.

If, while the eastbound train occupies preliminary section C—A, a westbound train 40 should enter preliminary section B—D, the consequent opening of track relay T would not cause signal relay R^E to open because contact 6 of this track relay is shunted by contact 12 of relay R^W which is already 45 open; hence, signal S^E would continue to indicate "proceed", thus allowing the eastbound train to enter the restricted territory.

It is sometimes desirable that when two 50 trains approach the restricted territory at substantially the same time, one of them should be given preference over the other as to entrance into the territory. To permit of such selection, I provide a shunt around contact 6 of each track relay T and T², which 55 shunts include respectively normally open, manually operable circuit controllers K and K'. Assume now that it is desirable to give preference to westbound trains; circuit controller K' would be closed by an operator, 60 thereby removing signal relay R^W from the control of track relay T². Then if an eastbound train should enter section C—A, it would not affect either signal and would be permitted to enter the restricted territory 65 A—B unless a westbound train has in the

meantime entered section B—D. In the latter event, that is, if two trains occupy the preliminary sections simultaneously, track relay T will cause signal S^E to indicate stop but track relay T² will not be effective to 70 control signal S^W so the latter will continue to indicate proceed, thereby allowing the westbound train to enter the restricted territory. This selection is effective regardless of which train is first to enter its preliminary 75 section.

Referring now to Fig. 2, I have here shown two parallel tracks E and E' over which traffic moves in the same direction, this direction being indicated by the arrow. As in Fig. 1, the space between points A and B is restricted territory in which only one train is to be allowed at a time, either on one track or the other. Each track is provided with a track circuit comprising the rails between A and B, the track relays for these track circuits being designated T' and T³. For each track I also provide a preliminary section C—A extending to the rear from the restricted territory, which preliminary sections are also provided with track circuits comprising track relays T² and T⁴ respectively. Traffic into the restricted territory on track E is governed by a signal S^E, and traffic into the same territory on track E' is governed by a signal S^F. Signal S^E is controlled by both relays T' and T³ for territory A—B, the circuit being from battery 3 through wires 22 and 23, contact 24 of relay T³, wire 25, contact 26 of relay T', wire 27, 90 signal S^E, wire 28 to battery. Hence, a train in territory A—B on either track will hold signal S^E at "stop". Signal S^F is likewise controlled by both relays T' and T³ for the restricted territory, and also by contact 30 of relay T⁴ for the preliminary section of track E'; the circuit for this signal is apparent and need not be traced. Hence, signal S^F, will be held at "stop" by a train in the restricted territory on either track and also by a train in the preliminary section on track E. I have also shown two signals S² and S³ for the preliminary sections of tracks E and E' which signals are controlled in the usual manner by relays T² and T⁴ for their respective tracks. 110

The operation of the system shown in Fig. 2 is as follows: A train on track E' entering preliminary section C—A places signal S³ at stop but has no effect on signals S^E and S^F. Then as this train enters restricted territory A—B it places both signals S^E and S^F at stop and holds them in that position until it leaves the territory, so that no other train on either track is permitted to enter this territory until the first train leaves. A train on track E entering preliminary section C—A places signal S² at stop and also signal S^F. Then as the train enters the restricted territory A—B it controls signals S^E and S^F in the same way that these signals are controlled 120 125 130

trolled by a train on the other track. Assume now that two trains simultaneously occupy the preliminary sections of the two tracks respectively. The train on track E 5 would hold signal S^F at stop so that the other train could not enter the restricted territory, whereas signal S^E would remain at proceed so that the first train (the one on track E) would be permitted to enter the restricted territory.

In this application I have shown only sufficient apparatus for the control of the signals to accomplish the desired purpose, namely, to prohibit the presence of more 15 than one train in the restricted territory at one time. It is understood, however, that if desired the signals may in addition be controlled by other means in accordance with the principles of any known forms of block 20 signaling.

Although I have herein shown and described only two forms of signaling system embodying my invention, it is understood that various changes and modifications may 25 be made therein within the scope of the appended claims without departing from the spirit and scope of my invention.

Having thus described my invention, what I claim is:

30 1. In combination, a railway having two or more tracks, a restricted territory thereon, signals for the several tracks for governing the passage of trains into said restricted territory, and means controlled by a train within said territory on any track for causing all of said signals to indicate stop.

2. In combination, a railway having two or more tracks over which traffic moves in opposite directions, a restricted territory on 40 said railway, signals for the several tracks for governing the passage of trains into said restricted territory, and means controlled by a train within said territory on any track for causing all of said signals to indicate stop.

3. In combination, a railway having two parallel tracks over which traffic moves in opposite directions, a restricted territory on said railway, a signal for each track for governing the passage of trains into said territory, a signal relay for each of said signals, a preliminary track circuit for each track extending to the rear from said territory and including a track relay, means for controlling each signal relay by the track relay of the preliminary track circuit for the other track, and manually controllable means for at least one of said signal relays for removing such signal relay from control by the track relay by which it is normally controlled.

4. In combination, a railway having two or more tracks, a restricted territory on said railway, signals for the several tracks for governing traffic into the restricted territory, 65 means controlled by a train within said ter-

ritory on any track for causing all of said signals to indicate stop, and means controlled by a train approaching said territory for causing the said signals for other tracks to indicate stop.

5. In combination, a railway having two or more tracks, a restricted territory on said railway, signals for the several tracks for governing traffic into the restricted territory, and means controlled by a train on one of 70 said tracks approaching said territory for causing the signals for the other tracks to indicate stop.

6. In combination, a railway having parallel tracks over which traffic moves in opposite directions, a restricted territory on said railway, signals for said tracks, and means governed by trains on said tracks for controlling said signals to limit the number of trains which may simultaneously occupy 75 said territory.

7. In combination, a railway having parallel tracks over which traffic moves in opposite directions, a restricted territory on said railway, a signal for each track for governing the passage of trains into the restricted territory, and means controlled by a train on each track approaching said territory for causing the signals for the other tracks governing traffic into said territory to indicate 80 stop.

8. In combination, a railway having two parallel tracks over which traffic moves in opposite directions, a restricted territory on said railway, a signal for each track for governing the passage of trains into said territory, a signal relay for each of said signals, a preliminary track circuit for each track extending to the rear from said territory and including a track relay, and means for controlling each signal relay by the track relay of the preliminary track circuit for the other track.

9. In combination, a railway having two parallel tracks over which traffic moves in opposite directions, a restricted territory on said railway, a signal for each track for governing the passage of trains into said territory, a signal relay for each of said signals, a preliminary track circuit for each track extending to the rear from said territory and including a track relay, means for controlling each signal relay by the track relay of the preliminary track circuit for the other track, and means controlled by a signal relay 110 when operated by a train on the other track for removing the other signal relay from control by the track relay by which it is normally controlled.

10. In combination, a railway having two parallel tracks over which traffic moves in opposite directions, a restricted territory on said railway, a signal for each track for governing the passage of trains into said territory, a signal relay for each of said signals, 115 120 125 130

a track circuit for each track comprising the track rails in the restricted territory and a track relay, and a preliminary track circuit for each track extending to the rear from said territory and including a track relay, means for controlling each signal relay by the track relay of the preliminary track circuit for the other track, and means for controlling each signal by the track relay for each track circuit in the restricted territory.

11. In combination, a railway having two parallel tracks thereon, a restricted territory on said railway, a signal for each track for governing the passage of trains into said territory, a preliminary track circuit for one track extending to the rear from said territory and including a track relay, and means for controlling the signal for the other track by the track relay of the said preliminary track circuit.

12. In combination, a railway having two parallel tracks thereon, a restricted territory on said railway, a signal for each track for governing the passage of trains into said territory, a preliminary track circuit for one track extending to the rear from said territory and including a track relay, track cir-

cuits for the tracks including the rails in the restricted territory and track relays and means for controlling each signal by the track relays for both of the track circuits of the restricted territory, and for controlling the signal for one track by the track relay of the preliminary track circuit for the other track.

13. In combination, a railway having parallel tracks, a restricted territory on said railway, signals for the tracks, and means governed by trains on said tracks for controlling said signals to limit the number of trains which may simultaneously occupy said territory.

14. In combination, a railway having parallel tracks, a restricted territory on said railway, signals for the tracks, and means governed by trains on said tracks for controlling said signals to permit only one train to occupy said territory at a time.

In testimony whereof I affix my signature in presence of two witnesses.

HERBERT A. WALLACE.
